UNITED STATES PATENT OFFICE.

MALCOLM H. HUBBACK, OF SEATTLE, WASHINGTON, ASSIGNOR OF ONE-SIXTH TO
NELSON SPARKS, OF SEATTLE, WASHINGTON.

INTERNAL-COMBUSTION ENGINE.

1,275,925.

Specification of Letters Patent. Patented Aug. 13, 1918.

Application filed December 28, 1917. Serial No. 209,176.

To all whom it may concern:

Be it known that I, MALCOLM H. HUBBACK, citizen of the United States, residing at Seattle, in the county of King and State of Washington, have invented a certain new and useful Improvement in Internal-Combustion Engines, of which the following is a specification.

My invention relates to improvements in internal combustion engines and the object of my invention is to provide an engine of comparatively light weight in proportion to the amount of power that it is capable of developing and one that has a high efficiency and is economical in its consumption of fuel.

A further object of my invention is to provide an engine that has a continuous annular cylinder adapted to rotate about a fixed tubular support whereby the momentum of the concentrically balanced cylinder and parts connected therewith will be utilized in reproducing a uniform speed and constant torque on the engine shaft thereby practically eliminating the vibrations of the same.

My invention consists in the novel construction, adaptation, and combination of parts as will be more clearly hereinafter described and claimed.

In the accompanying drawings Figure 1 is a view in elevation of an engine constructed in accordance with my invention;

Fig. 2 is a view of the same in cross-section on broken line 2, 2 of Fig. 1;

Fig. 3 is a view of the same in cross-section on broken line 3, 3 of Fig. 2;

Fig. 4 is a view in elevation of a duplex pinion embodied in my invention;

Fig. 5 is a view in cross-section of the duplex pinion on broken line 5, 5 of Fig. 4;

Fig. 6 is a view in elevation of an interrupted gear used in the construction of the engine; and

Fig. 7 is a view in cross-section of the interrupted gear on broken line 7, 7 of Fig. 6.

Referring to the drawings, throughout which like reference numerals designate like parts, the numerals 10 and 11 indicate the two halves or sections, respectively, of the casing of an internal combustion engine.

The sections 10 and 11 are provided with hub portions 12 and 13 within which are disposed suitable bearings 14 that are mounted for rotation on a fixed tubular shaft 15.

One of the hub members 12 is rigidly connected with an axially disposed shaft 16 that may be journaled in a suitable bearing, not shown, and that constitutes the shaft through which power generated by the engine is transmitted.

The peripheral portions of the casing sections 10 and 11 are suitably shaped to form an annular cylinder 17 and the two sections are secured together by bolts 18 that pass through peripheral flanges 19.

Disposed within the casing formed by the sections 10 and 11 and securely keyed to the shaft 15 are two interrupted gears 20 and 21 that are each provided, on diametrically opposite sides, with toothed sections 22 and 23 each of which sections 22 and 23 extend substantially one-fourth of the distance around the circumference thereof, as shown in Fig. 6, and each of which sections 22 and 23 is provided with thirteen teeth in the construction herein shown.

The spaces on the gears 20 and 21 between the ends of the toothed sections 22 and 23 are occupied by two arcuate members 24 and 25 that are concentrically arranged and present a smooth outer or peripheral surface of a diameter slightly greater than the outside diameter of the gear sections.

Disposed within the casing in concentric relation to the interrupted gears 20 and 21 are two internal gears or ring gears 26 and 27, each preferably having seventy-two teeth and being provided at six equi-distant points around the circumference thereof with pairs of spaced lugs 28 and 29, respectively, between which are mounted cylindrical pistons 30 to 41 inclusive that operate within the annular cylinder 17.

The peripheral portions of the ring gears 26 and 27 are flanged as at 43 so that shoulders 44 are formed to fit against corresponding shoulders in the casing and support the rings for rotation therein.

The flanged peripheral portions 43 extend outwardly through narrowed portions 45 in the casing and make a close fit so that gases due to the explosions in the cylinder cannot gain access to the gear chamber of the engine.

- Interposed between each of the internal gears and its corresponding interrupted gear are two double pinions each comprising a twelve toothed gear 46 and a fourteen toothed gear 47 that are formed integral or otherwise rigidly connected with each other and are mounted on bearing pins that are fixed in the casing.
- 15 The twelve toothed gears 46 are adapted to mesh with the internal gears 26 and 27 and the fourteen toothed gears 47 are adapted to mesh with the gear segments on the interrupted gears 20 and 21.
- 20 The double pinions are each provided on one side with an arcuate slot 48 formed to fit the members 24 and 25 and adapted to slide on such members when they are in contact therewith thereby serving to lock 25 the ring gear with which they are connected to the casing.

The pinions that engage with the ring gear 26 and interrupted gear 20 are disposed at diametrically opposite points and the pinions that engage with the ring gear 27 and interrupted gear 21 are disposed at diametrically opposite points and at right angles to the two pinions first mentioned.

The casing section 11 is provided at three equi-distant points with spark plugs 50 that are each connected by wires 51 with suitable contact devices 52 that are carried by the rotating casing and adapted to make electrical contact at predetermined points with 40 stationary terminals 53 on the shaft 15 so that suitable sparks are delivered at three points simultaneously for igniting charges in the cylinder.

The fuel charge is prepared in the usual manner and is drawn by suction through an opening 54 into the interior of the hollow shaft 15 from whence it passes through perforations 55 into a chamber 56 and is thence conducted through three radial pipes 57 to intake openings 58 in the cylinder 17 that are located at three equi-distant points midway between the points of entrance of the spark plugs 50.

55 Exhaust openings 60 are provided in the casing section 10 at points adjacent the inlet openings 58 as shown in Fig. 2.

In operation when the pistons are in the position shown in Fig. 2, charges are compressed at three different points between pistons 30 and 36, 32 and 38, and 34 and 40, respectively, and are just ready to be ignited by the spark plugs 50. When the explosion occurs the pistons 30 to 35 inclusive are all locked to the casing by reason of the engage-

ment of the slots 48 in the double pinions 65 with the arcuate members 24 and 25 on the interrupted gears and the pistons 36 to 41 inclusive are free to move in a clockwise direction, within the cylinder, the double pinions that engage therewith rolling over the interrupted gears.

When the explosion occurs the pistons 36 to 41 inclusive will move in a clockwise direction in the cylinder until they lap the exhaust ports 60 and will then be carried over the exhaust ports by the momentum of the moving casing far enough to cause the slots 48 in the respective pinions with which these pistons are connected to engage with the arcuate members 24 and 25 at which 80 points the pistons 36 to 41 inclusive will occupy the same relative position within the cylinder as the pistons 30 to 35 inclusive do in Fig. 2 and will be locked to the casing.

At the same instant that the pistons 36 to 41 inclusive begin to lap the exhaust ports 60 the slots in the pinions that the pistons 30 to 35 inclusive are connected with pass off of the arcuate members 24 and 25 and engage with the teeth on the interrupted 90 gears thus permitting the pistons 30 to 35 inclusive to move relative to the case into the position occupied by the pistons 36 to 41 inclusive in Fig. 2.

As the pistons 36, 38 and 40 are moved by the explosion in a clockwise direction within the casing the pistons 37, 39 and 41 will move away from the intake openings thereby drawing in a fresh charge of fuel behind them and compressing a previously drawn 100 charge before them which compressed charge will be ignited as the pistons 37, 39 and 41 come into the proper position relative to the spark plugs.

The double pinions are all secured to the 105 engine casing and the ring gears 26 and 27 are both in engagement with the twelve toothed pinions 46. The pinions engaging one ring gear are locked against rotation by the slots 48, engaging with the arcuate 110 members 24 and 25 and the fourteen toothed pinions 47 engaging with the other ring gear, are in mesh with the interrupted gears; hence the force of the explosion tends to move the pistons apart, and, by virtue of the 115 engagement of the twelve toothed pinions with the ring gears and the fourteen toothed pinions with the interrupted gears, the pistons that are not locked to the casing are permitted to move away from the pistons 120 that are locked to the casing, thereby carrying the casing forward through one-fourth of one complete revolution with respect to the shaft 15, while the pistons advance one-sixth of one complete revolution with respect to the casing.

It is obvious that this engine may be converted into a steam engine by providing suit-

able arrangements for admitting steam between two adjacent pistons at the proper instant of time.

The number of teeth on the several gears herein described have been specified for the reason that they form a very convenient gear ratio but it will be understood that these relations may be varied and that other changes in the form of construction and arrangement 10 of parts of this engine may be resorted to within the scope of the following claims:

What I claim is:

1. An internal combustion engine comprising a fixed shaft, an engine casing rotatably mounted thereon, an annular cylinder in said casing, a plurality of pistons disposed within said cylinder and movable therein with respect to each other, means for admitting fuel to said cylinder, means for igniting said fuel at predetermined points to cause certain of said pistons to be moved apart, and gear means coöperating with said pistons and said casing and said fixed shaft to rotate said casing in response to explosions between said pistons.
2. An internal combustion engine comprising a fixed shaft, a casing rotatable thereon, an annular cylinder in said casing, two independently movable sets of pistons disposed in the cylinder, all of the pistons of each of said sets being rigidly connected together, means for admitting fuel to said cylinder and exploding the same to produce relative movement between said two sets of pistons and gear means coöperating with said casing and said pistons and said fixed shaft to impart rotary motion to said casing in response to the relative movement between said pistons.
3. An internal combustion engine comprising a fixed shaft, a casing including an annular cylinder rotatably mounted on said shaft, interrupted gears secured to said shaft, internally toothed ring gear of larger diameter than said interrupted gears and concentric thereto, pinions interposed between said interrupted gears and said gears said pinions being mounted on bearings that are secured to the casing, means on said interrupted gears for locking said pinions against rotation during a portion of their travel around said interrupted gears, pistons carried by said ring gears and movable in said cylinders, means for admitting gasified fuel to said cylinders and means for igniting said fuel.
4. An internal combustion engine comprising a casing mounted for rotation on a fixed shaft, an annular cylinder formed in the periphery of said casing, interrupted gears secured to said fixed shaft said interrupted gears each having smooth arcuate sections formed thereon, internally toothed ring gears movable within said casing,

double pinions rotatably connected with said casing said double pinions each comprising two gearwheels of a different number of teeth the gearwheel with the greater number of teeth being adapted to mesh with an interrupted gear and the gearwheel with the lesser number of teeth being adapted to mesh with an internal gear and each of said gearwheels having a slot therein to engage with the arcuate sections of said interrupted gears, pistons carried by said ring gears and movable within said cylinders, means for admitting fuel to said cylinder and means for igniting said fuel.

5. An internal combustion engine comprising a fixed tubular shaft, a casing rotatably mounted on said shaft, an annular cylinder formed in the peripheral portion of said casing, interrupted gears secured to said shaft said interrupted gears each having two oppositely disposed toothed sections extending one-fourth of the distance around the diameter thereof and two oppositely disposed arcuate sections arranged between the toothed sections, internally toothed concentric ring gears movably disposed within said casing, double pinions rotatably mounted on bearings carried by said casing at four diametrically opposite points two of said pinions being interposed between each ring gear and its corresponding interrupted gear and each of said pinions being provided with a gear of a greater number of teeth adapted to mesh with an interrupted gear and a gear with a lesser number of teeth adapted to mesh with an internal ring gear and each of said pinions having slotted portions adapted to engage with said arcuate sections, pistons carried by said ring gears and movable within said cylinder, means for admitting fuel charges to the cylinder, and means for igniting said fuel charges.

6. An internal combustion engine comprising a fixed hollow shaft, a casing rotatably mounted on said shaft, an annular cylinder in the peripheral portion of said casing, two interrupted gears secured to said shaft each of said interrupted gears having two oppositely disposed gear sections each extending one-fourth of the distance around the circumference thereof and two smooth arcuate surfaces disposed between the gear sections, two internally toothed ring gears of larger diameter than said interrupted gears and concentrically mounted for rotation within said casing, two duplex pinions interposed between each of said ring gears and its corresponding interrupted gear and mounted for rotation on pins that are secured to said casing each of said duplex pinions comprising a larger gearwheel adapted to mesh with the interrupted gear, a smaller gearwheel adapted to mesh with the internal gear and a slot adapted to en-

gage with the arcuate sections of the interrupted gears to prevent rotation of said pinions, a plurality of pistons carried by each of said ring gears and movable within said cylinder, means for admitting gasified fuel to said hollow shaft, conduits through which said gasified fuel may be drawn by

suction into said cylinders, and igniting means carried by said casing for igniting the fuel.

10

In witness whereof, I hereunto subscribe my name this 15th day of December, A. D. 1917.

MALCOLM H. HUBBACK.
